US0D1047960S

(12) **United States Design Patent** (10) **Patent No.:** **US D1,047,960 S**
(45) **Date of Patent:** **** Oct. 22, 2024**

(54) **LOUDSPEAKER**

(71) Applicant: **LUXSHARE ELECTRONIC TECHNOLOGY (KUNSHAN) LTD.**, Kunshan (CN)

(72) Inventors: **Gan Ding**, Kunshan (CN); **Jinghuan Zhu**, Kunshan (CN); **Ruibao Liu**, Kunshan (CN)

(73) Assignee: **LUXSHARE ELECTRONIC TECHNOLOGY (KUNSHAN) LTD.**, Kunshan (CN)

(**) Term: **15 Years**

(21) Appl. No.: **29/892,157**

(22) Filed: **May 15, 2023**

(30) **Foreign Application Priority Data**

Nov. 23, 2022 (CN) 202230782618.3

(51) LOC (14) Cl. **14-01**

(52) U.S. Cl.

USPC **D14/204**

(57) **CLAIM**

The ornamental design for a loudspeaker as shown and described.

DESCRIPTION

FIG. 1 is a front side perspective view of the loudspeaker in accordance with our design.

FIG. 2 is a bottom side perspective view of the loudspeaker in accordance with our design.

FIG. 3 is a front view of the loudspeaker in accordance with our design.

FIG. 4 is a rear view of the loudspeaker in accordance with our design.

FIG. 5 is a left view of the loudspeaker in accordance with our design.

FIG. 6 is a right view of the loudspeaker in accordance with our design.

FIG. 7 is a top view of the loudspeaker in accordance with our design.

FIG. 8 is a bottom view of the loudspeaker in accordance with our design.

FIG. 9 is an enlarged view of portion 9 of the loudspeaker in accordance with our design.

FIG. 10 is an enlarged view of portion 10 of the loudspeaker in accordance with our design; and,

FIG. 11 is an enlarged view of portion 11 of the loudspeaker in accordance with our design.

The portions of the drawings shown in dashed lines form no part of the claimed design. The shade lines in the drawings show surface contour and not surface ornamentation.

1 Claim, 11 Drawing Sheets
